JEROME B. GARDNER, OF NEW YORK, N. Y.

Letters Patent No. 96,420, dated November 2, 1869.

BASE-BURNING COOKING-RANGE.

The Schedule referred to in these Letters Patent and making part of the same.

To all whom it may concern:

Be it known that I, JEROME B. GARDNER, of the city, county, and State of New York, have invented a new and useful Improvement in "Ranges for Cooking and Heating-Purposes," of which the following is a full, clear, and exact description, reference being had to the accompanying drawing, forming part of this specification, and in which—

Figure 1 represents a sectional elevation of a range, constructed in accordance with my invention, taken as indicated by the line *xx* in

Figure 2, which also is a sectional elevation of a range, taken at right angles to fig. 1, as denoted by the line *yy*.

Figure 3 is a partly-broken or sectional plan of the same.

Similar letters of reference indicate corresponding parts.

My invention consists in certain combinations and arrangements of the parts of the range, whereby great economy, utility, and efficiency are secured, the same including a grate, arranged within a surrounding water-case, and fed or supplied with fuel from above, by or through a tube arranged to pass through a steam-boiler, which is in communication with the water-case of the range, and serves to circulate steam for general heating and cooking-purposes, and which, together with a hot-water boiler, arranged in proximity to it, have disposed within them ovens, that have the draught made to circulate in a tortuous manner around them, but which, being located as specified, are maintained at a temperature but little above the boiling-point, by reason of the circulation kept up of the steam, as fast as it is generated in the steam-boiler, and draught upon the hot water in the adjacent boiler.

In the range represented in the accompanying drawing, which is constructed upon the base-burning principle—

A is the grate, that may be of conical or other form, and which is arranged within a water-case, B, that forms the lower walls of the range on or around all its sides.

Said grate is supplied with fuel by or through a vertical pipe, C, arranged over its centre, and provided with a damper, *a*, to prevent up-draught when opening, and upper lid, *b*, to feed in fuel.

The front portion, D, of the range may be provided with the usual openings and covers of cooking-stoves or ranges for various culinary purposes.

E is the ash-pan.

The back portion of the range, which stands erect upon the base or table-portion thereof, is made up in

part of a steam-boiler, F, which occupies the larger space of such erect and rear portion, as from *c* to *c* in fig. 3, while the remainder of the rear part of the range is composed of or includes a hot-water boiler, G.

The steam-boiler F is in free communication at its base with the water-case B, and has the fuel-feed pipe C embedded within or located to pass through it, which serves to heat the fuel in its way to the grate.

The steam, as rapidly as it is generated in this boiler, is passed, on opening a suitable cock for the purpose, by a pipe, *d*, to heat an outside steam-oven, H, and, furthermore, by a branch, *e*, when desired, to supply a vegetable-oven, I, from which latter it is allowed to escape, by a pipe, *f*, into the chimney, while the steam, after circulating around the oven H, is conveyed, by a pipe, *g*, to heat any number of apartments or rooms in the building, and afterward returned, in a condensed form, by a branch, *g'*, forming a continuity of the branch *g*, to the boiler, thus keeping up a steady or free circulation without waste or loss, and restricting the temperature of said boiler to but little over boiling-heat.

The hot-water boiler G, which serves to supply the building with hot water by an upper pipe, *h*, and is fed with water by a lower pipe, *i*, is of a close character, by not being in communication with the water-case B.

Both of these boilers have ovens, J J, let into them, with doors in front, and arranged in tiers, one oven above the other, and more or less exposed on their outsides to the water or water and steam in the boilers; also, having the flues *kk*, from the fire-place, arranged in a tortuous manner, to partially encircle each oven, the draught finally passing off by pipes, *ll*, to the chimney or main smoke-pipe, K.

The ovens J J, thus arranged within the boilers, will, by the free circulation or draught kept up from the latter, be maintained at a regular temperature, barely in excess of boiling-heat, which is the most desirable for cooking-purposes.

A range, thus constructed and provided, will be found most economical, convenient, and generally efficient.

What is here claimed, and desired to be secured by Letters Patent, is—

1. The arrangement of the grate A within the water-case B, forming the walls of the lower portion of the within-described range, substantially as specified.

2. The combination of the fuel-supply pipe C, the grate A, and the water-case B, essentially as shown and described.

3. The combination, with the water-case B, of the boiler F, and fuel-fed pipe C, let into or arranged to run through the latter.

4. The arrangement, within the boilers F and G, fitted with pipes to keep up a free circulation, of the ovens J J, in combination with the draught-flues k k, essentially as shown and described.

5. The combination, in a base-burning range, of

the water-case B, the grate A, arranged therein, the steam and hot-water boilers F G, and the ovens J J, substantially as specified.

JEROME B. GARDNER.
